Primary Examiner — Lauren D McVey*Assistant Examiner* — Mai Shim(57) **CLAIM**

The ornamental design for a paint roller as shown and described.

DESCRIPTION

FIG. 1 is a perspective view of a paint roller, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The dot-dot-dash broken lines depict portions of the article that form no part of the claimed design.

1 Claim, 3 Drawing Sheets(56)
